CLAIM

The ornamental design for billet aluminum triple trees for motorcycle forks, as shown and described.

DESCRIPTION

FIG. 1 is a perspective view of the billet aluminum triple trees for motorcycle forks showing the new design with an inserted illuminated panel;

FIG. 2 is a top view of the billet aluminum triple trees for motorcycle forks on a reduced scale;

FIG. 3 is a left side view of FIG. 2;

FIG. 4 is a back view of FIG. 2;

FIG. 5 is a front view of FIG. 2;

FIG. 6 is a right side view of FIG. 2; and,

FIG. 7 is a bottom view of FIG. 2.

The broken line showing of environmental features and a name tag is for illustrative purposes only and forms no part of the claimed design.
